Primary Examiner — Mark T. Philippss

CLAIM

The ornamental design for an electric outboard motor as shown and described.

DESCRIPTION

1. Electric outboard motor

1.1 : Front

1.2 : Back

1.3 : Left

1.4 : Right

1.5 : Bottom

1.6 : Top

1.7 : Perspective

1.8 : Perspective

1.9 : Enlarged view of portion 9

Protection is not sought for the matter shown by means of dotted lines, broken lines or coloring in the reproductions.
